UNITED STATES PATENT OFFICE.

JOHN WESLEY MACKNIGHT, OF NEW YORK, N. Y.

METHOD OF LAYING ARTIFICIAL PAVEMENTS.

SPECIFICATION forming part of Letters Patent No. 387,724, dated August 14, 1883.

Application filed June 28, 1888. Serial No. 278,394. (No specimens.)

To all whom it may concern:

Be it known that I, JOHN WESLEY MACKNIGHT, of New York city, New York, have invented a new and Improved Method of Laying Artificial Pavements, of which the following is a specification.

This invention relates to an improved method of laying an artificial pavement. Its object is more particularly to facilitate the formation of the curb and to form a lap joint between the various blocks.

The invention consists in the various features of improvement more fully pointed out in the claims.

15 In the accompanying drawings, Figure 1 is a top view of my improved artificial pavement, showing it in the process of laying. Fig. 2 is a vertical longitudinal section on line $x-x$, Fig. 1. Fig. 3 is a similar section, but with all the blocks finished. Fig. 4 is a vertical transverse section, on an enlarged scale, on line $y-y$, Fig. 1. Fig. 5 is a perspective view of part of the mold, and Fig. 6 is a perspective view of part of the joist.

25 In laying my improved pavement I first form a base of rocks, a , with an upper layer of coal-ashes b . These two layers constitute the foundation of the pavement, and they are spread evenly over the whole surface to be paved. After the foundation is in place, I place across it a number of joists, c , at such distances apart that the space between each pair of joists is equal to the width of each block to be formed. Each joist c has a downwardly-extending projection, c' , which extends over the foundation a b at the curb-line, Fig. 4—that is to say, each joist c extends over the layer b from house-line to curb-line, and is then bent down at the curb-line to reach to the

40 gutter-line. At the bend the joist c c' is shaped in longitudinal section exactly as the section of the completed block which is to be formed. Thus it is shown to be provided with two ar-
45 riss, c^2 c^3 , and with a bead, c^4 . The joists c have at each side a laterally-projecting flange, c^5 , projecting from end to end of the joist, and extending likewise down along projection c' . The flange c^5 runs along the upper edge of the joist, so that the joist is T-shaped in cross-
50 section, Fig. 2. After the different joists are put in place, I place over the alternate pairs of joists—that is, over joists 1 and 2, over joists

3 and 4, and over joists 5 and 6, &c.—a mold, d . This mold is of a size to reach from joist to joist, and it is cut out so as to conform exactly to the shape of the joist at its bend and its downward projection—that is to say, the parts c^2 , c^3 , and c^4 , that are represented positively on the joist, are represented negatively in the mold. Figs. 1 and 2 show two of the molds put in place for the formation of two blocks. In this way the joists and mold form at the bend of each block a chamber closed at its sides and top, but open at the end toward the house-line. The foundation, joists, and molds being thus all put in place, I fill the two top layers that complete the blocks into those spaces that are provided with the molds. In Figs. 1 and 2 the first and third spaces are thus filled in, and where the pavement is longer all the odd spaces would be similarly treated.

The two top layers consist of the lower layer e , composed of flinty concrete, and of the upper layer or dressing, f , composed of crushed trap-rock and cement. The lower layer, e , is packed upon the layer b on top of the foundation, and also around the curb. The height of this layer is such that it extends up to a level with the lateral flanges c^5 of the joists c . After the layer e is put in place, the top layer, f , is filled in to exactly fill the mold d , and to come up to a level with joists c . The blocks being thus completed, all the joists and the molds are removed. The right and left edges of each block will now be step shaped, Fig. 3, the layer e projecting beyond the layer f , and thus the flanges c^5 will be formed. The curbing of each block will also be molded to the required shape.

In order to fill out the intermediate spaces, the molds d are now placed across the same—that is, between the spaces formerly occupied by joists 2 and 3, middle space, Fig. 1, 4 and 5, &c., and the layers e and f are again filled in like manner, as has already been described with relation to the odd blocks, the only difference being that the joists are no longer used, their foundation being taken up by the edges of the blocks already formed. The intermediate blocks being thus finished, the molds d are removed and the pavement is completed.

It will be seen that in this pavement the in-

termediate or even blocks have their top layers, *f*, resting at each edge upon the flanges *e'* of the odd blocks. In this way the joints between every two adjoining blocks are broken. Water 5 will thus be more completely excluded, and the even blocks will be prevented from settling. It will also be seen that by the use of the joists working in co-operation with correspondingly-shaped molds the arris and the 10 bead on the corner of each block can be formed with great facility.

What I claim is—

1. The method of forming the curb of an artificial pavement, which consists in spreading 15 an even foundation forming a chamber by

mold and joists around the curb, that is open at its back, and filling the top layer into the chamber and between the joists, so as to extend around the front and over the top of the foundation, substantially as specified.

20

2. The process of laying an artificial pavement, which consists in forming flanges *e'* upon alternate blocks, and then filling in the intermediate blocks with their top layers, *f*, resting upon said flanges, substantially as specified.

JOHN WESLEY MACKNIGHT.
